Leon Goldmerstein, Inventor
By his Attorney, Dr. Becker

UNITED STATES PATENT OFFICE.

LEON GOLDMERSTEIN, OF NEW YORK, N. Y.

GAME.

1,204,006.

Specification of Letters Patent.

Patented Nov. 7, 1916.

Application filed January 24, 1916. Serial No. 73,995.

To all whom it may concern:

Be it known that I, LEON GOLDMERSTEIN, a subject of the Czar of Russia, and resident of the borough of Manhattan, in the city, 5 county, and State of New York, have invented certain new and useful Improvements in Games, of which the following is a specification.

This invention relates to an improvement 10 in the game of skill known as "checkers," my improvement consisting in the addition to said game of an element of chance, for the purpose of rendering the game more generally attractive and entertaining.

15 Checkers, as now played between two players of equal ability, will nearly always be won by the player having an initial advantage, because there are few opportunities for finesse, so that with both players avoiding errors, the game is practically assured to one player from the start, and has a generally uninteresting course.

20 The element of chance introduced by my improvement in the game of checkers consists (a) in the provision of certain designations on one side of the pieces, to be exposed when the ordinary pieces, by reason of their reaching the final row of squares on the opponent's side of the board, are to be accorded the functions of "king" pieces, instead of in the usual crowning method of imposing another ordinary piece upon said advanced piece; and (b), in having the king piece designations referred to, representative, in each player's quota of pieces, of equal 25 numbers of king pieces for each side. In other words, recognizing the game as comprising twelve white pieces and twelve black pieces, said pieces, on their obverse side, are 30 respectively white and black; while, on their reverse side the, so called, white pieces are divided into two sets of six pieces each, the pieces of one set bearing each an indication to represent a white king. The twelve black 35 pieces bear upon their reverse sides similar indications to also divide them into six black kings and six white kings. By these means 40 each player is equipped, at the start of the game, with equal friendly and inimical king 45 making potentiality; because, as the pieces are set for the game, the white side is seen to have all white ordinary pieces, and the black side all black ordinary pieces. Further, the pieces will have been shuffled before setting, to leave both players in ignorance as to the positions of the opposite king

making powers, which are indicated only upon the then hidden reverse sides of the pieces. Thus, in turning over a piece, to create for it the king value, upon reaching a 60 square in the final row, the factor of chance rules in determining whether said king will belong to the white side or the black side; and hence a new element is introduced into the game of checkers, to render its outcome 65 more uncertain and more entertaining.

In the drawing: Figure 1 shows a checker board upon which a game is in progress, the remaining pieces including some that have been moved to the final row of squares from 70 opposite sides, and there reversed to become kings. Fig. 2 is a perspective view of a white checker piece, obverse side uppermost, showing that the cylindrical surface of the piece bears the same color as its obverse side, 75 and Fig. 3 is a similar view of the same piece, reversed, but bearing an arbitrary indication of white king value.

The checker pieces *a* and *b*, respectively, 80 represent the white and black pieces commonly used in this game. The white pieces are white over one side, called the obverse, and over the side walls, so that when said pieces are resting upon the board, with the obverse exposed, the reverse side is hidden 85 from view. Said reverse side, on six of the white pieces, is marked in a particular manner, as at *c*, (Fig. 3) to represent white king value; and said reverse side, on the remaining six white pieces, is marked, as at *d*, to 90 represent black king value.

The black pieces correspond with the white pieces in that one side thereof (the obverse) and the walls, are black, and the reverse side, as to six of those pieces, is marked to indicate black king value; the remaining six black pieces having their reverse side marked to indicate white king value. Of course, the representative markings on the reverse side of the pieces, both white and black, to indicate 95 king value therefor, may be of any desirable character. As an example of the arbitrary markings that may be employed, I have shown in the drawing the white king value as represented by a white center surrounded by a black margin; and the black king value as represented by a black center 100 surrounded by a white margin.

Obviously my said improvements may be employed with pieces used in other games, 110 analogous to checkers, using reversible play pieces, and my invention is therefore not

limited to use in the game of checkers. Also, when my improved play pieces are employed in the usual game of checkers, the number thereof, for each side, having opposing king 5 value designations, may range from one upwardly, according to the fancy of the game designer. In this manner the element of chance introduced by my invention in the game of checkers, is variable within wide 10 limits. Conceivably, a player may be handicapped by the set of pieces including a smaller number thereof with king value for his side than for his opponent's side. Other variations may be resorted to within the 15 spirit and scope of my invention.

I claim:

1. A set of pieces for the game of checkers, in which each piece is provided, at one side thereof, with indications of king value, 20 half the number of said pieces representing white kings by said indications, and the other half black kings.
2. A set of reversible play pieces for the

game of checkers, wherein each piece has indications representing different play values 25 upon its opposite sides, the indications on one side of some of said pieces representing "white" king value, and on the others "black" king value.

3. A set of reversible play pieces for the 30 game of checkers, wherein each piece has on one side a representation of ordinary checker value, and on the other side a representation of king value, the white pieces including some with "white" king value and some 35 with "black" king value, and the black pieces including some with "black" king value and some with "white" king value.

Signed at the borough of Manhattan in the city, county and State of New York this 40
21st day of January, A. D. 1916.

LEON GOLDMERSTEIN.
